UNITED STATES PATENT OFFICE

2,009,293

LUBRICATING SYSTEM FOR NEEDLE-
THREAD TAKE-UP MECHANISMS

George A. Fleckenstein, Stratford, Conn., assignor to The Singer Manufacturing Company, Elizabeth, N. J., a corporation of New Jersey

Original application July 7, 1932, Serial No. 621,200. Divided and this application February 1, 1934, Serial No. 709,253

6 Claims. (Cl. 112—256)

This invention relates to lubricating systems for the needle-thread take-up mechanism of sewing machines and has for its object the provision of a lubricating system which will constantly supply lubrication to the thread take-up mechanism of high speed sewing machines.

With the above and other objects in view, as will hereinafter appear, the invention consists in the devices, combinations, and arrangements of parts hereinafter set forth and illustrated in the accompanying drawings of a preferred embodiment of the invention, from which the several features of the invention and the advantages attained thereby will be readily understood by those skilled in the art.

This application is a division of application Serial No. 621,200, filed July 7, 1932, which has matured into Patent #1,955,580.

In the accompanying drawings—

Fig. 1 is a front elevation of the head, with the face-plate removed, of a sewing machine having my improved lubricating system embodied therein.

Fig. 2 is a horizontal section taken substantially along the line 2—2 of Fig. 1.

Fig. 3 is a side elevation, partly in section showing the relation of the parts.

Fig. 4 is a fragmentary sectional view showing the positions of the lubricant-conducting wicks.

Fig. 5 is a detailed sectional view.

In the embodiment of this invention selected for illustration, 10 indicates the overhanging arm of a sewing machine which terminates in the usual hollow head 11 within which is disposed the take-up mechanism and the operating means for the needle-bar. As shown, the main shaft 12 is rotatably journaled in a bearing bushing 13 in the arm 10 and has secured to its end by the set screws 14 a counterbalancing disk 14 having a rigidly attached crank-pin 15 disposed with its axis offset from the axis of the shaft 12. A needle-bar 16 extending through a suitable bearing 17 in the bottom of the head 11 is operated by the usual pitman 18 having one of its ends pivoted to the crank-pin 15 and its other end pivotally secured to the needle-bar by the pivot-screw 19.

The take-up mechanism of the present invention includes a disk 20 rigidly secured to the crank-pin 15. Adjustably attached to the disk 20 by the elongated slots 21 and screws 22 is a second disk 23 formed with a crank-pin 24. Rigidly fixed to the crank-pin 24 is a third disk 25 having a crank-pin 26.

Fixed to the boss 27 on the head 11 by the set-screw 28 is a headed stud 29 disposed with its axis parallel to the axis of the needle-reciprocating or main-shaft 12. Mounted to reciprocate on the stud 29 is a rocking member 30 having a split upstanding lug 31 (Figure 1) suitably apertured to receive the cylindrical bar or rod 32 which is clamped in place by the screw 33. Secured to the rocking member 30 by the screw 34 is a take-up arm 35 having its free end 36 laterally offset and the offset end provided with thread-eyes 37. The rod 32 has a pivotal and sliding connection with the crank-pin 24. As shown, a bent crank-arm 38 has one of its ends pivotally connected with the crank-pin 24 and its other end formed with a bore arranged transverse to the axis of the pin 24, the rod 32 being slidably fitted in the bore. It will be obvious that as the shaft 12 is rotated the rod 32, rocking member 31, and the take-up lever 35 are oscillated about the stud 29.

On the opposite side of the head 11 is an apertured boss 39 in which is secured by the set-screw 40 a headed stud 41 having fixed thereon a rocking member 43 provided with a depending split-lug 44. The rocking member 43 is apertured to receive the cylindrical rod 45 which is held in place by the clamping action of the screw 46. The cylindrical rod 45 has its free end laterally offset as shown at 47 and the offset portion is provided with thread-eyes 48. The cylindrical rod 45 constitutes, in effect, a second take-up lever and it is pivotally and slidably connected with the crank-pin 26 by a bent crank-arm 49 having one of its ends pivotally connected to the crank-pin 26 and its other end formed with a longitudinal bore which slidably receives the rod or take-up lever 45.

From the foregoing it will be observed that the take-up levers 35 and 45 are oppositely directed, and are fulcrumed to swing concomitantly in the same direction about their horizontal axes 29 and 41 which are disposed at opposite sides of and parallel to the needle-reciprocating shaft 12. In other words the take-up levers have alternate movements about their pivots simultaneously in a clockwise direction followed by a simultaneous movement in a counterclockwise direction during each rotation of the main-shaft, and that the take-up levers are actuated from the needle-reciprocating shaft 12 to and from a position in which the levers are in alignment with each other by a balanced actuating mechanism which is afforded by the provision of diametrically opposite crank-pins 24 and 26 carried by the needle-reciprocating

shaft. It will also be observed that the oppositely directed movements of the take-up levers multiply the take-up and slack-giving action upon the thread, thereby requiring only relatively short take-up levers which reduces the vibration of the ends of the levers.

To prevent accidents in case of breakage when the machine is operated at high speeds, the take-up levers and their operating means are completely enclosed in the head of the machine excepting the extensions 36 and 47 by a face-plate 50 having arcuate slots 50' through which the lateral offset ends 36 and 47 of the take-up levers extend.

To provide means for lubricating the bearing, crank-arms and crank-pins, I have provided a lubricant reservoir 60 in the bearing 13 which may be filled through the plug 61. The reservoir 60 is filled with waste or other fibrous material which lubricates the shaft 12 direct. Some of the lubricant in the reservoir flows through the aperture 62 and along the longitudinal bore 63 in the shaft 12 thence through the conduit 64 to the crank-pin 15. The excess lubricant thrown off by the bearing 13 is collected in a depression 65 from which it flows by gravity through the lubricant conducting conduit 66 to the lubricant reservoir 67. To lubricate the pivot-pin 29 and the cylindrical rod 32 lubricant-conducting wicks 68 and 68' are provided. The wick 68 has one of its ends depending in the lubricant reservoir 67 and its other end threaded through the duct 69 in the pivot-pin 29 which is provided with an aperture 70 through which the lubricant escapes to the bearing surface of the rocking member 30. The wick 68' supplies lubricant to the lubricating pad 71 which is fixed to the boss 72 on the head of the machine by the screw 73.

To lubricate the pivot-pin 41 a wick 74 is provided having one of its ends depending in the lubricant reservoir 67 and its other end threaded through the longitudinal bore 75 in the pivot-pin 41. The bore 75 connects with aperture 76 through which the lubricant escapes to the bearing surface of the rocking member 43. A second lubricating pad 71 secured by the screw 79 and plate 80 to the boss 78 on the head 11 of the machine is provided to lubricate the rod or take-up lever 45. A wick 81 having one of its ends depending in the lubricant reservoir 67 supplies lubricant to the pad 71. It will be evident that the lubricant is drawn by capillary attraction from the reservoir 67 through the wicks 68 and 74 to the bearing surfaces of the rocking members 30 and 43, and that lubricant is supplied to the lubricating pads 71 and 77 by the wicks 68' and 81. It will also be evident that the rods 32 and 45 are lubricated by contacting the lubricating pads 71 and 77 when they reach their extreme positions as shown in Fig. 1.

To lubricate the bearing surfaces of the crank-pins 24 and 26, I have provided two lubricant conduits 82 and 83 which are secured in suitable apertures in the head of the machine. The conduits 82 and 83 are provided with wicking 84 and 85 which extend out of the free ends of the conduits. The hub of the crank-arm 49 (Figure 5) has a lubricant-receiving aperture 86 which communicates with an aperture 87 in the crank-pin 26. The aperture 87 conducts the lubricant to the fiber filled lubricant chamber 88 in the crank-pin 26. The crank-pin 24 is provided with a longitudinal bore 89 which is filled with fibrous material and communicates with a lubricant-conducting aperture 90. It will be obvious from the

foregoing that the crank-arms 38 and 49 wipe against the wicks 84 and 85 during each revolution and that the lubricant is conducted through the apertures 86 and 90 to the bearing surface of the crank-pins 24 and 26 and to the fiber filled reservoirs 88 and 89 from which it is further distributed to the bearing surface through apertures 87 and 90'. A third lubricant conduit 91 carrying a wick 92 which contacts the periphery of the disk 20 and supplies the disk with a film of lubricant which flows down the side of the disk to further lubricate the crank-pin 15.

From the foregoing description it will be obvious that the elements employed are susceptible of material variations. The privilege is therefore reserved of resorting to all such legitimate changes therein as may be fairly embodied within the spirit and scope of the appended claims.

Having thus set forth the nature of the invention, what I claim herein is:—

1. A balanced take-up mechanism for sewing machines comprising, a plurality of pivot-pins, a plurality of take-up levers pivoted thereon, means for swinging said take-up levers about their pivots, and means for lubricating the bearing surfaces of said pivot-pins, said lubricating means comprising lubricant-conducting wicks each having one of its ends depending in a lubricant reservoir and the other of its ends threaded through a duct communicating with the bearing surface of its respective pivot-pin.

2. In combination, a sewing machine having a main shaft, a pair of diametrically opposite crank-pins carried thereby, a pair of pivot-pins, a pair of take-up levers pivoted thereon, a pair of crank-arms connecting said take-up levers with said crank-pins, and means for lubricating the bearing surfaces of said crank-pins, said last named means comprising a lubricant reservoir provided with depending wicks and apertures in said crank-arms which receive lubricant from the wicks during each revolution of the main-shaft.

3. A sewing machine having a frame including a bracket-arm having a rotary shaft journaled therein, said bracket-arm terminating in a hollow head provided with a lubricant-collecting chamber, stitch-forming mechanism including a reciprocating needle-bar journaled in said head, a needle-thread take-up member, a mechanism for actuating said take-up member from said rotary shaft, a lubricant-dispensing pad disposed within the hollow head in a position to be intermittently engaged by said take-up actuating mechanism, and a lubricant-conducting wick extending from said chamber to said pad.

4. A sewing machine having a frame including a bracket-arm having a rotary shaft journaled therein, said bracket-arm terminating in a hollow head provided with a lubricant-collecting chamber, stitch-forming mechanism including a reciprocating needle-bar journaled in said hollow head, a vibratory needle-thread take-up member, a guide-rod rigid with said member, a sleeve slidably embracing said guide-rod, a rotary crank pivotally carrying said sleeve to thereby reciprocate said sleeve lengthwise of said guide-rod to actuate the take-up member, a pad disposed within said head in a position to dispense lubricant to said guide-rod and sleeve, and a lubricant-conducting wick extending from said chamber to said pad.

5. A sewing machine having in combination, a frame including a bracket-arm terminating in a hollow head, a stationary lubricant reservoir located interiorly of said head, a shaft journaled

in said bracket-arm, stitch-forming mechanism including a reciprocatory needle-bar journaled in said hollow head, a needle-thread take-up member, means for actuating said member from said shaft, and a plurality of wicks disposed in the hollow head and extending from said reservoir exteriorly of and to said actuating means for conducting lubricant to said actuating means.

6. A sewing machine having in combination, a frame including a bracket-arm terminating in a

hollow head, a lubricant reservoir located within said head, a rotary shaft journaled in a bearing in said bracket-arm, a vibratory take-up member, mechanism actuated by said shaft for vibrating said take-up member, said mechanism being disposed above the lubricant reservoir, and wicking for conducting lubricant upwardly by capillary attraction from said reservoir to said mechanism.

GEORGE A. FLECKENSTEIN. 10
